UNITED STATES PATENT OFFICE.

FREDERICK HEATHER, OF FULHAM, LONDON, ENGLAND.

EXHAUST SILENCER FOR INTERNAL-COMBUSTION OR OTHER ENGINES.

Application filed September 15, 1926, Serial No. 135,673, and in Great Britain October 3, 1925.

This invention relates to exhaust silencers more particularly for use with internal combustion engines, which devices, as is well known, receive the exhaust gases and act upon them so as to extract their kinetic energy with a view to minimizing the noise attendant upon their discharge into the atmosphere.

The invention has particular relation to silencers of the kind in which the gases are caused to flow in a serpentine or wave-like path during their passage from an inlet to an outlet or point of discharge.

One object of the present invention is to provide an improved exhaust silencer of this kind, the improvements being particularly directed to an improved manner of constructing the apparatus whereby the same can be readily built up and dismantled to facilitate cleaning, which may become necessary after the apparatus has been in service for some time, in order to remove deposit which may have accumulated.

A further object of the invention is to so construct an exhaust silencer as to act on the gases passing through the apparatus in an improved manner so as to reduce to a minimum back pressure on the engine and more efficiently to extract the kinetic energy remaining in the gases.

A feature of the invention consists in an exhaust silencer comprising a plurality of similar sections or units of tubular form arranged in end to end relation and adapted to provide a path for the gases of serpentine or wave-like form having the interior space of each section or unit progressively and continuously diminishing in cross-sectional area from the part where the gases enter the space to the outlet or part where they leave said space, said outlet being located at the end of and to one side of said space.

A further feature of the invention consists in an exhaust silencer comprising a plurality of similar hollow sections or units arranged in end to end relation and assembled in such relation in a tubular member adapted to fit the exterior of the sections, the latter being such that a path is provided for the gases of serpentine or wave-like form.

More specifically each tubular section or unit is provided on its interior with an inclined or curved guiding or baffle surface

adapted to cause the gases to eddy, whirl or partake of the form of a vortex, which surface extends from one side of the section or unit towards and terminates at the inner side of an outlet in the form of a restricted throat so as eventually to direct the gases to said opening or throat, whence they pass into the next unit or section, it being appreciated that the sections or units are of similar form whereby a similar action is produced as referred to above in all the sections or units.

The sections are preferably assembled together in a manner permitting their ready dismantling and it is pointed out that a further advantage flowing from the sectional or unit construction is that a silencer can be built up with only as many of said units or sections as are necessary effectively to deal with the exhaust gases of a particular engine.

Thus it will be understood that when the number of units or sections has been determined for a particular type of engine, other silencers adapted to deal with the exhaust gases of similar engines can be rapidly and economically manufactured.

The reduced openings or throats may be staggered or displaced from each other around a central longitudinal axis of the apparatus so that the gases, besides being caused to pass through the apparatus in the manner above set forth, also travel transversely so that the flow of the gases through the device may, for example, be in a somewhat zig-zag or helical manner from the inlet to the point of discharge.

In the latter case the assembled sections may be mounted for rotation together on a longitudinal axis so that the action of the flow of the gases through the apparatus will be to cause rotation of the section, which rotation as will be appreciated may be utilized in any manner desired.

I am aware that a silencer has been proposed consisting of a series of cups fitting one within another, the outer walls of the cups forming a casing and the solid ends of the cups forming division plates or walls which were perforated alternately on opposite sides to insure a zig-zag baffling passage.

It has also been proposed to form an exhaust box or silencer of a series of dome-like

plates which had the form of paraboloids of revolution fitted one into another by cylindrical rim portions and arranged so that there was an intervening space between each 5 plate. The parabolic part of each plate was perforated towards one side with small holes and the plates were arranged so that the perforated portion of each plate was opposite the unperforated portion of the adjacent 10 plate or plates. The plates were enclosed by a cylinder which held the plates in place by engagement with the last of the dome-shaped member.

Referring now to the accompanying drawings which illustrate improved forms of exhaust silencer constructed according to the invention:

Figure 1 is a plan view of one form of the invention;

Figure 2 is a plan view partly in section of a modified form;

Figure 3 is a plan view of a further modified form;

Figure 4 is a sectional elevation of one of the sections or units;

Figure 5 is an end view of Figure 4 looking in the direction of the arrow A;

Figure 6 is an end view of Figure 4 looking in the direction of the arrow B;

Figures 7 and 8 are respectively sectional side and end elevations of a modified form of section or unit that may be employed;

Figure 9 is a sectional elevation of a modified form of silencer, and

Figures 10 and 11 are detail views hereafter referred to.

In carrying out the invention according to one mode there are provided a plurality of sections or units *a* of tubular form and 40 similar shape. Each section or unit is fully open at one end *b* but narrows down as shown at *d* from the central portion to form at the opposite end and side a narrow throat or reduced opening *c*, so that, considering two 45 sections assembled together in alignment, the throat or reduced outlet opening *c* of one section opens into the fully open end *b* of the next section, it being appreciated that the interior surface of the narrowed down portion 50 provides an inclined or curved baffle or guide surface which causes the gases to eddy, whirl or partake of the form of a vortex and eventually directs them to the throat in the manner substantially as shown by the arrows in Figures 1, 2 and 3.

The edges *e* of the fully open end *b*, the narrowed down portion *d* above referred to and the extreme edges *f* of the throat are of a form such that when, for example, two 60 sections are placed together end to end in reversed relation the edges of the open end *b* of one section overlap and closely fit against the narrowed down portion of the other section *d*, thus providing two chambers 65 connected only by the restricted opening or

throat *c*. When, therefore, a number of sections are arranged together in a similar manner to that just described for two sections or units, gases passing in at one end will flow, generally considered, in a serpentine or wave-like path from one end to the other.

The edges of the fully open end may be contained in a plane inclined to the longitudinal axis and extending from one side of 70 the section to within a short distance of the opposite side thereof as shown in Figures 7 and 8, or they may be curved as shown at *e* (Figure 4) while the remaining portion *g* of the said edges may be contained in a central vertical plane. Similarly, the narrowed down portion *d* of the section or unit may be contained in a plane similarly inclined in an opposite direction to the longitudinal axis and extending to the part where it merges 75 into the throat, Figures 7 and 8, the edges of the throat being contained in a vertical plane similar to the remaining portion of the edges of the open end above referred to, so as to be coterminous with the latter when two sections are placed end to end.

As will be readily understood by so forming the sections or units any number thereof (according to requirements) may be placed together end to end and secured together in 85 any suitable manner to form a complete silencer.

It is to be understood, however, that the said edges of the open end of the tubular member and the narrowed down portion need 90 not be contained in a plane surface but may be curved so as to be of S shape, as shown at *d*, Figures 1 to 6, in a manner appropriate for their overlapping and closely fitting one another when placed end to end.

A complete silencer is built up of a number of these sections or units formed as described above and placed end to end in series. They may conveniently be assembled within a tubular member *g*, suitable provision being made for preventing them from movement endwise and from rotation within the tubular member, such provision being such as to enable their ready removal from the tube for purposes of cleaning.

There are preferably also provided end pieces forming receiving and discharge passages for the gases. These end pieces (Figure 10) consist of a pair of similar parts *h* semicircular in cross-section, each part having a pair of lugs *i* and *j*. Two of these parts which may be of sheet metal are seamed, brazed or otherwise secured together along their edges *k* and by means of bolts extending through lugs *i* and *j* they are clamped 105 to the tubular member *g*. The parts forming the end pieces are preferably each provided with a shoulder *l* to abut the end of the tubular member *g* so as to facilitate proper assembly and reassembly of the end 110

pieces with the tubular member g , while a second shoulder x is provided for the end piece that is secured to the exhaust pipe so as to facilitate its proper assembly there-

5 with. The construction described provides a convenient manner of readily assembling and dismantling the apparatus, the device being secured to the exhaust pipe of the motor in any appropriate and well-known 10 manner. It is to be understood, however, that the end pieces may be cast as a whole, if desired.

According to a modified form of the invention the sections together with the tubular member may be mounted to rotate on the 15 end pieces as shown diagrammatically in Figure 9, in which the tubular member g' is mounted for rotation on ball or other suitable bearings mounted in said end pieces. 20 The throats are then arranged in a helical manner around the axis of the tube as shown in dotted lines.

A part of the kinetic energy of the exhaust 25 gases will thus be expended in rotating the sections or units and said tubular member, it being understood that this rotation can be utilized for any purpose desired.

It is to be understood, however, that such spacing of the throats may also be employed 30 in the case in which the sections are fixed so that the gases besides moving in a path of serpentine or wave-like form, will also be caused to travel transversely across the chamber when passing from one throat 35 through a chamber to the next throat.

I further contemplate building up a silencer composed of a number of elements 40 each of which consists of a plurality of said sections or units arranged end to end, and securing said elements together side by side and providing them with a common inlet and outlet so as to divide the gases into a plurality of streams of serpentine or wave-like 45 form, which discharge into a common outlet. This form of the invention is shown in Figures 2 and 3 in which two elements are provided, each of which consists of a tubular element within which are arranged a plurality of sections or units in the manner described above. The end pieces, however, in 50 this form of the invention are in the form of breeches pieces as illustrated in Figure 11, so as to provide a common inlet and outlet for the gases which flow in parallel through 55 the two elements.

The elements may be arranged as shown in Figure 3 so that the length of the path for the gases in the individual elements differs slightly as, for example, by varying the number of sections or units in each element, whereby the streams of gases are not synchronized so that the final exit from the individual elements takes place in cyclic order instead of simultaneously, thereby producing 60 a constant or even flow of the gases

through the common outlet. This arrangement reduces the pulsation of the discharge of the gases considerably and renders such discharge almost noiseless.

The individual sections or units may be 70 formed from short lengths of tubing of appropriate gauge which are cut and pressed to the shape above referred to but it is to be understood that they may be made in any other convenient manner as by casting or 75 stamping from sheet metal and bending them into the desired shape or in any other appropriate manner.

It is to be understood that the shape and size of the individual elements may be varied 80 to suit particular requirements of engine and pressure of the exhaust and that the number of units employed may also be varied to suit such requirements.

Having now described my invention, what 85 I claim as new and desire to secure by Letters Patent is:—

1. An exhaust silencer comprising a plurality of similar sections of tubular form arranged in end to end abutting relation and 90 adapted to provide for the gases an undivided path of wave-like form having the interior space of each section progressively and continuously diminishing in cross-sectional area from the part where the gases 95 enter the space to the part where they leave said space the last mentioned part constituting an outlet and being located at an end of and to one side of said space.

2. An exhaust silencer comprising a plurality of similar hollow sections arranged in end to end abutting relation and assembled in such relation in a tubular member adapted to fit the exterior of the sections, the interior of the latter being such that an undivided 105 path is provided of wave-like form.

3. An exhaust silencer as claimed in claim 1, wherein said reduction in cross-sectional area is produced by a curved baffle surface 110 which extends from the part where the gases enter the space to the outlet.

4. An exhaust silencer as claimed in claim 1, wherein the said sections are such that the gases enter said space substantially midway of its length and are directed to the 115 opposite side thereof to the outlet where they leave said space.

5. An exhaust silencer as claimed in claim 1, wherein said reduction in cross-sectional area is produced by a baffle surface of **S** 120 shape.

6. An exhaust silencer as claimed in claim 1, wherein said sections are of a shape such that they are adapted to overlap each other longitudinally when placed end to end.

7. An exhaust silencer as claimed in claim 1, wherein said sections overlap each other in such a manner that the end edges of each section remote from the reduced outlet overlap and fit against the reduced portion of 130

an adjacent section, which reduced portion ranged side by side and provided with a by its interior surface, provides a curved common inlet adapted to conduct the gases 10 in parallel to the elements.

8. An exhaust silencer as claimed in claim 5, 1, comprising a plurality of elements each comprising a plurality of such sections arranged end to end, said elements being ar-

In testimony whereof I have signed my name to this specification.

FREDERICK HEATHER.
